SAFETY GARMENT

George Bailhe, Brooklyn, N. Y.

Application February 25, 1949, Serial No. 78,269

2 Claims. (Cl. 9—20)

1

This invention relates to garments generally and particularly to life saving or safety garments.

While garments provided with inflatable portions or with life preserver attachments are known in the art, such devices invariably have the tendency, when depended upon to support the wearer within water, to so float his body that his head and especially the mouth and nose are not always kept clear of the water, as it should be for proper safety, whereby such garments are rendered impractical and even dangerous.

Furthermore, heretofore employed devices of that type are invariably restricted to their intended purpose of assisting the wearer to float, and can not be worn as a part of ordinary clothing when not in use as floating help.

The present invention contemplates to overcome the faults and shortcomings of buoyancy-providing devices of that kind and to introduce a garment which not only will assure the person wearing it to securely float so that not only his head, face, mouth and nose will be always kept safely above water and prevented from becoming submerged, but that his chest area will be caused to float topmost, thereby the possibility of an inadvertent turning of the body with the head downward is definitely precluded.

It is also contemplated to so construct the safety garment of the present invention that it may serve both as a buoyancy-providing device and as clothing for ordinary wear when not in use for floating. In addition it is contemplated to employ the garment, when worn as clothing, to protect and warm the chest and neck, for which function the garment is partly inflated so that insulating layers of air are formed in the respective portions of the garment.

To that end the present invention provides a readily attachable over-garment which may be worn either without or on top of ordinary clothing, and which over-garment can be readily secured by a fast-working slide fastener arranged in the front, and in which garment are provided means for tightening it to the body interiorly about the waist of the wearer, thereby preventing its shifting in respect to the wearer's body, and in which garment are provided relatively large and broad, readily inflatable chest-supporting elements and a neck-supporting element, which latter connects the chest supporting elements, the combined elements assure the correct and safe support of both the head and of the chest of the wearer above water, and definitely prevent the possibility of tumbling of the body in the water or causing the submerging of the head.

2

The prime object of this invention therefore is the provision of a safety garment having relatively large float supports extending over the chest portion and around the neck of the wearer, and wherein the neck support is connected with the chest-supporting portions.

Another object of this invention is to provide a safety garment with a continuous inflatable element composed of two relatively voluminous chest-supporting portions and a substantially designed neck-supporting portion, which latter forms a connection between the two chest-supporting portions.

15 A further object of this invention is the provision of a safety garment in combination with a continuous, inflatable element, composed of a pair of relatively large chest-supporting portions and a substantially designed neck-supporting portion, which latter connects these chest portions, and wherein the neck portion is provided with means for readily inflating or deflating the entire inflatable element when desired.

An additional object of this invention is to provide a safety garment of the type indicated which is made of relatively waterproof material and in which are provided inner and outer layers at the front of the garment and inner and outer layers at the top back of the garment, and wherein the collar structure of the garment is made hollow by employing two separate upper or outer and lower or inner plies, which are united exteriorly, and wherein the two-ply front sections of the garment are so constructed that they provide relatively large, circumferentially closed pockets, which are open at their top ends, and which top ends communicate with the hollow collar formation, and which pockets and the hollow collar are adapted for the reception of an inflatable bladder having two large chest portions, one for each pocket, and a neck structure connecting the chest portion, said neck structure being adapted to be insertable into the hollow collar formation of the garment, and wherein the neck structure of the bladder is provided with a tubular extension equipped with a suitable valve for inflating or deflating the bladder, said collar formation having an opening for the passage therethrough of that tubular extension, and wherein the neck structure of the bladder and the collar formation of the garment are provided with corresponding fastening means for fixing the position of the bladder in respect to the garment.

Still another object of the present invention is to provide in a garment of the class indicated, 55 an interior fastening element in the form of a

draw string arranged in the vicinity of the waistline of the garment and being intended for tightening the garment against the wearer's body below the chest portion of the garment to prevent its shifting in respect to the wearer's body.

A further object of this invention is to provide a readily closeable and readily openable slide fastener connection between the two front portions of the garment.

A still further object of this invention is to provide a safety garment of the kind indicated, wherein the material of the garment is made from water-impervious material, such as a plastic film, and wherein, instead of a removable bladder, the garment is constructed with two peripherally sealed plies about the chest and collar portions, whereby an integral bladder formation is produced in the garment, and which bladder formation is provided with suitable means for readily inflating or deflating it from without the garment.

A further object of the present invention is to provide a safety garment of the class indicated, wherein the under or lower ply of its hollow collar portion is normally drawn together at the rear and is rendered expansible to accommodate the inflated neck structure of the bladder.

The foregoing and still further objects and important provisions of the present invention will become more fully apparent from the ensuing description, in conjunction with the accompanying drawings, wherein:

Fig. 1 is a front elevation of a closed garment designed according to the present invention;

Fig. 2 shows the closed garment with its bladder inflated, while worn by a person;

Fig. 3 is a front elevation of the garment in its open state and showing its interior arrangement;

Fig. 4 is a section taken approximately along line 4—4 of Fig. 3;

Fig. 5 is an enlarged section along line 5—5 of Fig. 3 through the collar portion of the garment;

Fig. 6 is a diagrammatical vertical cross section through the garment with an inflated bladder;

Fig. 7 is a rear view of the top portion of the garment showing the arrangement of the collar construction;

Fig. 8 illustrates a plan view of the bladder in its deflated state;

Fig. 9 is a section taken approximately on line 9—9 of Fig. 3;

Fig. 10 illustrates a fragmental elevation of a modified safety garment made from plastic material; and

Fig. 11 is a section taken approximately along line 11—11 of Fig. 10.

Considering now the garment in detail, reference is being had to the different figures, wherein numerals 10 and 11 denote the left and right front sections of the garment, which latter are made in two layers of waterproof material, that is outer layers 10' and inner or lining members 11' as clearly seen from Figs. 4 and 9. These double layers or plies extend full-length from the shoulders and collar areas to the bottom edges of the frontal sections and are provided with a slide fastener closure 12. The back section of the garment, indicated at 13 in Fig. 3, is made of one-ply material, but at its upper portion there is provided a relatively narrow lining member or flap 14 extending from its top edge 15 to its bottom edge 16 a short distance below. That bottom edge is free and may be readily

lifted, in the direction indicated by arrow I, for the insertion of the bladder, as will be explained presently.

At the top of the garment there is provided a hollow collar formation 17, as clearly illustrated in Fig. 5, composed of outer or top and under or back portions, 17' and 17'', respectively, the latter portion being cut relatively full so that it may be gathered by means of an elastic 18 attached along the upper edge of back section 13. The gathering of the back collar material renders the collar formation stretchable or expansible. To the interior edge of the outer collar portion is attached the upper edge 15 of narrow back lining member 14.

At the interior waistline area of the garment there is provided an elongated pocket 19 for the reception of a draw cord 20, which latter may be fastened together before the garment is closed by slide fastener 12. The exterior or normally upper surface of collar formation 17 is preferably provided with a suitable covering, such as corduroy, although any other type of material may be employed, or such covering may be omitted if so desired.

Referring now to the construction of front sections 10 and 11, as stated above, each are preferably composed of an outer ply and an inner ply or lining, which plies are peripherally united and in addition are stitched together along lines 21, to form deep chest pockets 22. These pockets are circumferentially closed, except for their top ends, which latter are open and communicate directly with the hollow interior of collar formation 17 and the space between back section 13 and lining flap 14. By lifting that flap access is provided to that space.

Bladder

Bladder 23, shown in detail in Fig. 8, comprises two symmetrically arranged chest portions 24 connected with each other by neck portion 25. The latter is provided with a snap fastener element 26, a grip tab 27 and a short tubing 28, at the end of which is secured a valve 29, whereby the bladder may be either inflated or deflated. Bladder 23 is preferably made from two plies of plastic material, the edges of which are firmly united by heat-sealing, thus rendering the bladder watertight.

Insertion of bladder

The bladder is intended to be associated with the garment so that its two large chest portions 24 are placed into pockets 22 and neck portion 25 is inserted in the hollow space of collar formation 17 of the garment. To facilitate the insertion of the bladder, lining flap 14 is lifted and the two chest portions 24 are inserted first into pockets 22, whereupon neck portion 25 is moved into collar formation 17 where it is held in place by means of snap fastener element 26, upon its engagement with a corresponding snap fastener element 26', provided at the center and near the edge of collar formation 17. It will be noted that the latter is provided with a buttonable tab 30, made of two plies of material, and the edge of the tab is left open sufficiently to facilitate the passage to without of valve 29 at the end of inflating tube 28. Collar tab 30 is intended to be normally attached to button 31 when the collar is in its normally downward position as shown in Fig. 1. When the garment is being worn while the bladder is either fully or partly inflated, the collar may be brought up as shown

in Fig. 2, in which case tab 30 is attached to button 32 provided near the right tip of the collar.

As stated, the garment of the present invention is adapted to normally form a part of the clothing of the wearer and may be either worn on top of the usual clothing, or may be used instead of such clothing. Due to the fact that bladder 23 extends over practically the entire chest area of the wearer and about the neck of the latter, which portions of the garment are constructed of two plies, the garment affords, even without a partly inflated bladder, considerable protection of the wearer's body. When the bladder is partly inflated the latter forms an effective insulating layer around the chest and neck portions and enhances the warming effect at those areas. Thus the garment may form an effective protection while worn outdoors and especially on board of ship and while it is not serving as a life saving device. In that case the bladder may be partly inflated. In the event of emergency the garment is readily adapted to support the wearer's body in water, in which event the bladder is to be fully inflated. The chest formations of the bladder will support the wearer in water so that his chest will always be topmost in the water, and the inflated neck portion will support the head comfortably above the water surface. In no event is there a tendency of tumbling the wearer's body with the head down, but on the contrary the garment will cause the body of the wearer to float with the chest and head up, thereby precluding the possibility of drowning due to submersion of the head.

In order to enhance the warming quality of the collar portion and render it more comfortable for wear, the outer layer of the garment collar is preferably covered with cushioning material, such as corduroy, as already indicated above.

Referring now to Figs. 10 and 11, these illustrations picture a safety garment made entirely from plastic material, such as "vinylite." In this embodiment bladder formation 23' constitutes an integral part of the frontal garment sections and of the collar portion, which latter serves as communicating element between the chest portions of the bladder formation. The front of the garment is again provided with a slide fastener 12', and around the waist there is formed a pocket 19' for the reception of a draw cord. As will be seen from Fig. 11, the front sections of the garment are made from inner plies 33 and outer plies 34, and bladder formation 23' is produced by heat-sealing the two plies, as at 35, so that the upper ends of the thus-formed pockets remain open and communicate with the hollow interior of the collar. It will be also noted that the collar structure is expandible by providing a fullness in material at the back of the collar, which is normally drawn together by an elastic 18'.

Although the garment construction shown in Figs. 10 and 11 is not as "dressy" as the one described above, it is nevertheless suited for use as an overgarment and possesses the quality of warming the chest and neck portions of the wearer due to its two-ply arrangement in these areas, which latter will give added protection to the wearer while the bladder formation is either deflated or partly inflated. Extending from the collar of the garment is a tubular element 28' terminating in a valve 29', in the manner provided in the bladder shown in Fig. 8. The collar is preferably equipped with a tab 30',

however the latter need not serve for housing tubing 28', as is the case in the embodiment described previously, but may be used, when buttoned to the bottom ply of the collar, to hold the tubing out of sight.

While in the foregoing safety garment structures are described in accordance with the present invention, the specific details indicated are by no means intended in a limiting sense, inasmuch as improvements and changes may be readily incorporated therein, without departing from the broad scope of this invention as covered by the annexed claims.

I claim:

1. In a safety garment, an outer layer including a back panel and two front panels secured along their rear edges to the back panel, said front panels being provided with slide fastener closing means along their front edges, full-length lining members for the front panels, corresponding in shape and size to the latter, secured along their rear, front and bottom edges to the edges of the front panels, a relatively narrow lining member extending along the upper portion of the back panel, a hollow collar formation composed of outer and under portions, the upper edge of the narrow back lining member being secured to the interior edge of the outer collar portion so that an inverted back pocket is formed between that lining member and the back panel and which pocket communicates with the hollow collar; chest pockets formed by stitching together the material of the upper chest areas of the full-length front lining members and of the front panels, said chest pockets being closed circumferentially except at their top, the top openings of the chest pockets communicating with the hollow collar formation by way of said inverted back pocket; and a continuous inflatable element inserted into said chest pockets and the hollow collar formation; said collar formation being adapted to normally lay flat against the neck and shoulder areas of the garment but being further adapted to be turned upwards and to be held in its upturned position when said element is inflated.

2. In a safety garment as in claim 1, said inflatable element comprising two relatively small chest portions and a relatively short but wide neck portion connecting the chest portions, the latter substantially corresponding to the uppermost chest areas of the wearer of the garment, said neck portion and said collar having coacting, interengageable means located substantially at the center of their respective outer edges for keeping the inflatable element at its correct central position relative the garment while the said element is either inflated or deflated.

GEORGE BAILHE.
